UNITED STATES PATENT OFFICE.

PARKER COOK, OF WASHINGTON, DISTRICT OF COLUMBIA, AND WILLIAM E. WINE, OF TOLEDO, OHIO.

TANK-SIPHON.

1,229,720.

Specification of Letters Patent. Patented June 12, 1917.

Application filed July 7, 1916. Serial No. 107,951.

To all whom it may concern:

Be it known that we, PARKER Cook and WILLIAM E. WINE, both citizens of the United States, PARKER Cook residing at 5 Washington, District of Columbia, and WILLIAM E. WINE residing at Toledo, State of Ohio, have invented certain new and useful Improvements in Tank-Siphons, of which the following is a specification.

10 Our invention relates to new and useful improvements in siphon valves and especially to an arrangement for emptying tank cars.

As is well known the general practice is 15 to provide a tank car with a valve at the bottom thereof and to empty the tank by gravity, that is provide a valve at the bottom of the car which is operated from the top thereof after the dome cover is open.

20 There are however many objections to the present form of valves employed at the bottom of the tank car, for the reason that in a number of instances the valve has become jammed off its seat, which resulted in the 25 loss of the entire amount of gasoline in the tank car and on several occasions resulting in great property loss and also loss of life.

One of the objects of our invention therefore is to provide a valve mechanism whereby the tank is emptied by a siphon arrangement, and wherein it will be impossible for the car in transit to be relieved of its load of oil, or gasoline, or other fluid until a 35 vacuum is first formed and which vacuum has to be started by a manual operation.

Another object of our invention is to provide a valve arrangement whereby the flow of gasoline or oil from the tank can 40 not be started until the dome cover is opened, thus avoiding any accidental flow or discharge of the contents of the tank until desired; and also to provide an arrangement whereby if for any reason it is 45 desired to stop the flow or discharge of the tank, it is simply necessary to destroy the vacuum in the improved valve arrangement to be hereinafter fully described.

Still another object of our invention is 50 to provide a siphon valve arrangement for tank cars whereby there is no vacuum in the valve arrangement when the dome cover is closed thereby preventing any accidental discharge of the contents of the tank.

Still another object of our invention is to 55 provide a tank car with the improved discharge arrangement that may be easily started, and that may be easily stopped by the breaking of a vacuum, and wherein it will be impossible for any loss of the contents of the tank car unless the car should 60 happen to be damaged by a wreck, etc.

Still other objects of our invention are to provide a siphon arrangement that may be quickly and readily installed in the tank 65 cars now in general use, or that may be quickly and easily provided in any forms of new tank cars and at the same time comply with all the requirements set out by the Master Car Builders' Association. 70

With these and other objects in view our invention consists in certain new and useful improvements and combination of parts as will be hereinafter more fully described and pointed out in the claims. 75

In the drawings Figure 1 is a vertical section of the improved tank siphon arrangement.

Fig. 2 is a similar view but with the parts in a different position. 80

Fig. 3 is a transverse sectional view taken on line 3—3 of Fig. 1.

Fig. 4 is a top plan view of the base member of the improved tank siphon. 85

Fig. 5 is a sectional view taken on line 5—5 of Fig. 2.

Fig. 6 is a detail view of the upper operating member of the bottom valve, and

Fig. 7 is an enlarged detail sectional view of the valve located at the upper part of 90 the siphon and showing in dotted lines the valve in its closed position.

Referring now to the drawings:

A dome 1 of the ordinary form used on tank cars is shown having an opening and 95 a cover 2 at the top thereof.

It is to be understood that the form of dome or tank car form no part of the invention and the hereinafter described arrangement may be successfully used with any of 100 the general forms now in use.

Secured preferably centrally to the bottom of the tank is a casting 3 which will be hereinafter termed the "base member" and as will be seen is riveted as at 4 after a portion has been cut out of the bottom of the tank, the said cutout portion being of nearly 105 the same diameter of the base member.

This base member 3 is preferably a unitary casting having the flange 5 at the upper portion thereof which flange is riveted as before mentioned to the bottom of the tank car. 5 In the bottom of this base member 3 is the discharge opening 6, which is extended and the outer portion is shown as threaded externally as at 7 for the reception of a cap or nipple, so that a further discharge pipe 10 may be secured thereto. Slightly above the threaded portion 6, the base member widens at one side so that a valve 8 may be pivoted as at 9, which valve is operated by the tap-pet or stem 10, the lower portion of which 15 extends through the opening 11 in the base member 3 and the lower portion of said stem 10 normally forcing the outer end 12 of the valve 8 downwardly and thereby forcing the closing portion 13 of the valve 20 against the valve seat 14 formed centrally of the base member 3.

The said base member 3 has as shown a centrally located vertically extending tubular portion 15, which tubular portion extends 25 above the level of the sides of the base member 3. This member is preferably cast integral with the base member and is imperforate at its bottom or in other words if so arranged that it is not possible for any fluid 30 that comes within the base member to get within the said tubular portion 15 excepting that it pass up through the top member and down into the tubular portion 15 which action will be hereinafter described. 35 This tubular portion 15, is preferably internally threaded as at 16, and secured therein is the pipe 17, the lower end of which is externally threaded as at 18, and the upper end of which is designed to extend 40 above the fluid level of the tank.

Referring for the moment again to the base member 3, it is to be noticed that the central tubular portion 15 is also provided on its outer surface with four guide members 45 19 which members tend to strengthen the central member 15 and also to guide a casing 20 in its upward and downward movement.

This casing 20 as will be noticed is preferably threaded at its upper end as at 21 to fit within what I term the cap member 22, which cap member is internally threaded at its lower portion as at 23, and said cap and casing incloses the pipe 17, but the said casing 20 is open at its lower end.

It will be remembered that the pipe 17 is threaded at its lower end to the member 15, and that the casing 20 is threaded to the cap member 22 at its upper end, so that any 60 variance in sizes of the different tank cars may be easily met, all that it is necessary to change, if the cars are of different height, being the lengths of the pipe 17 and casing 20.

Referring now to the cap member 22, it

will be also noticed that this may be a unitary or solid casting, and in the top of which is pivoted a handle 24. Also formed in this cap member are the guide members 25 which are provided with the stops or shoulders 26 so that it will be impossible for the cap 22 to drop lower than the said shoulders 26. 70

Also formed on the lower portion of the cap member 22 are the shoulders 27, which shoulders are adapted to contact with a brace or guide member 28, which is secured to the inner surface of the dome, as at 29, this guide member 28 securely holding the cap member 22 in an aligned vertical position; also 80 by providing the shoulders 27, as mentioned it is impossible to raise the said cap member 22 and the casing 20 connected thereto above the position as shown in Fig. 2.

By using this member 28, the inner guide 85 members 25 in the cap portion 22, and the lower guide members, a very rigid construction is obtained which of course is desirable in an article of this kind.

A further brace member 30 is shown the 90 ends of which member are fastened to the member 28 and which member partly surrounds the cap member 22 and is also provided with a flanged portion 31 through which passes the upper end of the aforementioned stem 10. This stem has provided near its upper end and directly beneath the flange member 31 a spring 32, which is held in place by the stop or washer 33. At the upper end of this stem is a handle 34 which 95 is irregularly shaped, and said stem is normally held by the spring 32 in its downward position to normally hold the lower valve in its closed position. A movement of the handle 34 at the top of the stem 10 100 however will draw the stem 10 upwardly thus allowing the lower valve 8 to open.

Referring again to the top casing 22 it will be seen that in its upper end is the opening 35 in which opening there is secured a valve 36 which valve is provided with a handle 37 and it is to be especially noticed that when this handle 37 is in its upward position the valve is closed, and when the handle is in its downward position, the 110 valve is open. 115

In other words it is impossible to close the cover 2 unless the handle 37 is pushed downwardly and the valve is then and must be, in its open position. 120

A description of the operation of our improved mechanism is as follows:

Supposing the tank car be full of gasolene, and the cover 2 locked in position. The gasolene will of course fill the base and will pass up between the inner pipe 17 and the outer casing 20 up to the normal level of the car, as it is to be remembered that the vent or valve 36 is in its open position or the cover could not be closed. 125 130

In other words the parts and the level of oil will be in the position as clearly shown in Fig. 1.

Supposing now it is desired to empty the car of its load.

The cover 2 will then be opened and the operator will first operate the handle 37 to thereby close the opening in the top cap 22. The operator will then grasp the handle 24 and pull upwardly on the same thereby lifting the cap 22 and the casing 20 upwardly until the shoulder 27 comes in contact with the brace and guide member 28. As the upper valve member 26 is closed, and as the lower valve member 8 is also normally closed, the upward movement of the cap 22 and the casing 20 will form a partial vacuum in the pipe 17 and in the top of the cap 22, which vacuum will pull the oil or gasoline up in the space between the pipe 17 and casing 20 into the top cap and it will then flow into the pipe 17.

The operator will then grasp the handle 34 and open the lower valve 8 and the oil will then flow out of the pipe 17, thus starting the siphon and will in this manner discharge the entire contents of the car. When the operator releases the upper handle 24, the top cap and casing 20 will of course lower themselves but will in no way effect the siphon arrangement. If for any reason it is desired to cut off the flow of gasoline, it will be only necessary to open the valve 36 at the top which would break the vacuum 35 in the cap and in the inner pipe 17 and the flow would of course instantly stop.

Also the valve 8 might be operated to close the flow at the bottom but it is just as simple to break the vacuum as above mentioned.

It is to be noticed that when the car is in transit and the dome cover locked down, the valve 36 will be open and even should the valve 8 become disarranged or jammed 45 or in any manner forced off its seat, there will be absolutely no loss of the contents of the car as to get into this inner pipe 17 it is necessary that the cap 22 be manually lifted and that the upper valve be closed 50 which cannot happen if the dome cover be closed.

From the above it will therefore be seen that with our improved arrangement it is impossible for the loss of the contents of 55 the car unless the entire bottom casing was ripped off of the car and even should the bottom valve become jammed or held open still no loss of gasoline can occur, at the same time the arrangement is such that the 60 flow may be easily and quickly started, or as easily discontinued as before described.

Mere colorable changes may be made without departing from the spirit and scope of the invention.

Having thus described our invention what

we claim as new and desire to secure by Letters Patent is:—

1. A pipe adapted to pass through the bottom of a tank and also extending upward above the fluid level of said tank, said pipe being normally closed at its lower end, an enlarged casing fitting over the upper end of said pipe and capable of vertical movement to thereby form a vacuum in said pipe and means independent of the casing for opening the lower portion of said pipe to thereby siphon the contents of said tank. 70 75

2. In combination with a tank car provided with a dome, a pipe adapted to pass through the bottom of said tank car and also extend upward into the said dome, an enlarged casing fitting over the upper end of said pipe and capable of vertical movement to thereby form a vacuum in said pipe and means independent of the casing for opening the lower portion of said pipe to thereby siphon the contents of said tank car. 80 85

3. In combination with a tank car provided with a dome and dome cover, a pipe adapted to pass through the bottom of said tank car and also extend upward above the fluid level of said tank into said dome, an enlarged casing in said dome and fitting over the upper end of said pipe and capable of vertical movement to thereby form a vacuum in said pipe, means for opening the lower portion of said pipe to siphon the contents of said tank and means connected to the said casing to prevent a vacuum in said pipe when said dome cover is in its normal 90 95 position. 100

4. In combination with a tank car provided with a dome and dome cover, a tubular portion extending through the bottom of said tank car and extending upwardly into said dome, said tubular portion normally closed at its lower end, said pipe open at its upper end, a casing open at its lower end and fitting over the upper end of said passageway, said casing capable of vertical movement to form a vacuum in said tubular portion, said casing provided with a valve in its upper end, said valve provided with means obstructing the closing of said dome unless the valve is in its open position, and means at the lower end of said tubular portion for opening the same to thereby siphon the contents of said tank. 110 115 120

5. A tank siphon comprising a base member, a cap member, a pipe extending upwardly from said base member, said cap member inclosing said upwardly extending pipe and provided with a downwardly extending casing also surrounding said pipe and said casing open at its lower end, a valve 125 in said base member independent of said cap for normally closing the upwardly extending pipe, said cap and casing capable of vertical movement to thereby form a vacuum in said pipe member. 130

6. A siphon for tank cars comprising a base member provided with an upwardly extending tubular portion, said tubular portion closed with relation to said base member, said tubular portion open at its upper end, a casing normally extending within said base member and surrounding said tubular portion, said casing closed at its upper end, said casing capable of vertical movement, a valve located in said base member to normally close said tubular portion and means without the casing and tubular portion for operating said valve.
7. In combination with a tank car provided with a dome and dome cover, a base member secured to the bottom of said tank car and extending below the lower level of said tank car, a tubular portion in said base member and extending above the upper level 70 of said base member and the bottom of said tank car, a pipe fitting within said tubular portion extending upwardly and into the dome of said tank car, a casing open at its lower end and closed at its upper end fitting 75 over said pipe and said casing capable of vertical movement, a brace member fitting within said dome and contacting with said casing to retain the said casing in its vertical position, means on said casing adapted 80 to contact with said brace member to thereby limit the movement of said casing and a valve located in said base member for normally closing the tubular portion in said base member.
8. In combination with a tank car provided with a dome and dome cover, a pipe extending downwardly through the bottom of said tank car, a valve at the bottom of said pipe, a cap member and casing open at 85 its lower end surrounding said pipe and capable of vertical movement, a brace member secured to said dome for retaining the said casing in its vertical position and also for limiting the upward movement of said 90 casing, said brace member also provided with a projection at one side, said projection provided with an opening for the reception of means to operate the valve at the bottom of said pipe.
9. In combination with a tank car provided with a dome and dome cover, a base member secured to the bottom of said tank car, a pipe extending into said base member and upwardly into said dome and closed 95 with relation to said base member, a casing open at its lower end also extending into said dome, said casing capable of vertical movement, a valve secured within said base member, said base member provided with an 100 opening and a rod extending within said opening in base member, the lower end of which contacts with said valve, a support in said dome for retaining the said casing in its vertical position and said support also 105 provided with an opening for the reception 110 of said stem, a spring on said stem for normally holding the valve in its closed position and means for allowing the stem to move upwardly to thereby open the valve in said casing.
10. In combination with a tank car provided with a dome and dome cover, a pipe secured to said base member, and means for normally closing the pipe in said base member, a cap member and casing passed over 115 the upper end of said pipe and said casing open at its lower end, said cap member limited in its upward movement and said cap member limited in its downward movement, a valve at the top of said cap member, said valve being provided with a handle, said handle when said valve is closed extending above the normal level of said dome, and means extending upwardly from said base member to operate the valve in said base 120 member.
11. A siphon for tank cars having a dome, comprising in part a base member, and a cap member, a pipe secured to said base member, and a casing secured to said 125 cap member, said casing and said cap fitting over said pipe, said casing and cap capable of vertical movement, means secured to the dome for retaining the cap member in its vertical position and means in the base member for retaining the said casing in a vertical position.
12. A siphon for tank cars comprising in part a base member, said base member forming a receptacle for fluid, an upwardly extending tubular portion in said base member and closed with respect to the contents of said base member, said tubular portion extending above the normal level of said base member, a valve pivoted in said base member, and said base member having an enlarged vertically extending portion provided with an opening therein and means extending in said opening to operate said pivoted valve.
13. In combination with a tank car provided with a dome, a base member, a casing, a pipe extending upwardly from said base member into said dome, said casing surrounding said pipe and open at its lower end and normally extending down into said base member, below the lower fluid level of said tank car, a valve independent of said casing and operated from said dome in said base member normally closing the said pipe, said casing capable of vertical movement to thereby form a vacuum in said pipe.
14. In combination with a tank car provided with a dome and a dome cover, a siphon arrangement in said tank car extending into said dome, and said siphon arrangement being in operable condition only, when said dome cover is in an open position.
15. The combination of a tank car provided with a dome and a dome cover, a

siphon arrangement fixed in said tank extending into said dome, a valve in said siphon arrangement and operated by a lever extending into said dome, a valve in the head of said siphon arrangement which may be closed only when said dome cover is open.

16. The combination of a tank car provided with a dome and a dome cover, a siphon arrangement disposed in said tank

car extending into said dome, the head of said siphon arrangement when operated extending beyond the top of the dome so that the same may not be operated unless the dome cover is open.

15
